UNITED STATES PATENT OFFICE.

JENNIE MOIR, OF BRISTOL, SOUTH DAKOTA.

CHURN.

No. 886,836.

Specification of Letters Patent.

Patented May 5, 1908.

Application filed September 10, 1907. Serial No. 392,230.

To all whom it may concern:

Be it known that I, JENNIE MOIR, a citizen of the United States, residing at Bristol, in the county of Day, State of South Dakota, have invented certain new and useful Improvements in Churns; and I do hereby declare the following to be a full, clear, and exact description of the invention, such as will enable others skilled in the art to which it appertains to make and use the same.

This invention relates to new and useful improvements in churning and in its broad conception it comprises a churn of the rotating body type which is formed with a surrounding water jacket, the object of the invention being to provide a novel construction, combination and arrangement of parts.

The details of construction will appear in the course of the following description in which reference is had to the accompanying drawings, forming a part of this specification, like characters of reference designating similar parts, throughout the several views, wherein:

Figure 1 is an elevation of a churn constructed in accordance with the present invention. Fig. 2 is an elevation looking at the side of the frame of such churn. Fig. 3 is a sectional view taken vertically through the churn body. Fig. 4 is a section on the line 4—4 of Fig. 3 illustrating the arrangement of the body and jacket outlet cocks.

In the accompanying drawings, the numeral 5 designates a supporting frame including the vertical standards 6, constructed at their upper ends as bearings for the trunnions 7 carried by the churn proper, one of said trunnions being extended to receive a detachable crank handle 8 employed for rotating the churn. The latter comprises an inner body 9, and an outer body 10 surrounding the body 9 in spaced relation, so that a jacketed space 11 occurs therebetween.

The bodies 9 and 10, at their lower ends have connection with a common bottom 12. Leading from the interior of the body 9 is a pipe 13 which projects through the jacket 11 and the body 10 and carries a turning plug 14, the pipe 13 being employed to drain buttermilk from the body 9. A pipe 15 leads from the space 11, the pipe 15, having a turn-

ing plug 16, and serving to permit of the drainage of water from said space. The body 9 at its upper end is threaded internally as at 17 and exteriorly as at 18. A cap 19 is employed to close the body 9 and is constructed with external threads 20 for engagement with the threads 17. The cap 19 likewise has a handle 21 to permit of its convenient manipulation. A cap 22 is employed to close the space 11. The cap 22 is of substantial ring shape and is concavo convex in cross section, the inner edge portion of said cap being formed with threads 23, for engagement with the threads 18. The outer edge portion of the cap 22 overlies the body 10 and is provided on its inner face with an inset rubber packing gasket 24. The outer face of the outer edge portion of the ring 22 is milled as at 25, whereby said cap may be conveniently removed.

In use, the space 11 is filled with water. In the summer time, the water is cold to prevent the butter from becoming soft and in winter time, the water is warm to facilitate the formation of the butter.

The invention is simple in its structural details, inexpensive to manufacture and practical and efficient in use.

From the foregoing description it will be seen that simple and efficient means are provided for accomplishing the objects of the invention, but while the elements herein shown and described are well adapted to serve the functions set forth, it is obvious that various minor changes may be made in the proportions, shape and arrangement of the several parts, without departing from the spirit and scope of the invention as defined in the appended claims.

What is claimed is:

A churn comprising a body having spaced inner and outer annular walls forming an inner milk chamber and an outer water chamber, a disk plate secured to the lower extremities of the walls to form an end closure for the chambers, said inner wall having threads on its inner and outer faces at the opposite open end of the inner chamber, a removable cap having exterior threads engaging the threads in the inner face of said inner wall, and a removable annular ring member forming a cap of inverted U-shape in cross

section, and in threaded engagement with the threads on the outer face of the inner wall and overhanging the upper edge of the outer wall to close the water chamber, said ring member adapted to surround the first mentioned cap whereby the latter can be removed without disturbing the ring member.

In testimony whereof, I affix my signature, in presence of two witnesses.

JENNIE MOIR.
